UNITED STATES PATENT OFFICE.

BERT H. W. HUCKNALL, OF ELYRIA, OHIO, ASSIGNOR TO THE AMERICAN LACE MFG.
CO., OF ELYRIA, OHIO, A CORPORATION OF OHIO.

DESIGN FOR LACE.

Application filed October 4, 1922. Serial No. 3,879. Term of patent 3½ years.

To all whom it may concern:

Be it known that I, BERT H. W. HUCKNALL, a citizen of the United States, and a resident of Elyria, in the county of Lorain and State of Ohio, have invented a new, original, and ornamental Design for Lace, of which the following is a specification, reference being had to the accompanying drawing, forming part thereof.

The figure is a plan view of a piece of lace, showing my new design.

I claim:—

The ornamental design for lace, as shown.
BERT H. W. HUCKNALL.
